UNITED STATES PATENT OFFICE.

EDWIN G. DANIELS, OF CHICAGO, ILLINOIS, ASSIGNOR TO THE CLEVELAND PUNCH & SHEAR WORKS COMPANY, OF CLEVELAND, OHIO, A CORPORATION OF OHIO.

PUNCH-PRESS.

1,260,652.

Specification of Letters Patent. Patented Mar. 26, 1918.

Application filed November 25, 1914. Serial No. 873,933.

To all whom it may concern:

Be it known that I, EDWIN G. DANIELS, a citizen of the United States, residing at 10853 Prospect ave., in Chicago, county of 5 Cook, and State of Illinois, have invented new and useful Improvements in Punch-Presses, of which the following is a specification.

This invention relates to improvements in 10 punch presses, and more especially to that part of the press which operates directly upon the piece of work which is being punched. A punch press of the type to which this invention more particularly relates 15 comprises a suitable frame structure supporting a reciprocatingly movable head which carries a tool, comprising a toolholder and a punch or die, for driving into or through the work; and the device also includes 20 mechanisms for raising and lowering the driving head at the will of the operator, such mechanisms not constituting any part of the present invention. In the use of such a press upon large and heavy pieces of work 25 difficulty is usually encountered in accurately locating the pieces to be punched with respect to the punching tool in order that the latter may strike in the right place. Heretofore presses have been made in which the 30 tool, after being withdrawn from the work, is again lowered and allowed to rest momentarily upon the work and then raised from the work. This invention provides a reciprocating head in which the tool holder 35 is carried in such manner that it is released at the end of the up-stroke of the reciprocating head, allowing the punch to drop down upon the work and remain continuously and freely resting upon such work to aid in 40 properly locating the same. As stated above, presses have been made heretofore in which the punch, after the operative stroke, is allowed to rest momentarily on the work and is then raised. In such devices, if the work 45 is not properly located during such time, the operator must wait until the punch again descends upon the work before he is able to further adjust the same; thus losing the time that the punch is off the work. In this 50 invention, after the operative stroke, the punch is allowed to rest continuously on the work, thus permitting the operator to use all the time to adjust the same and accomplish this as quickly as possible. Upon 55 the work being thus adjusted the reciprocating

head is allowed to again descend on an operative stroke grasping the tool holder on this stroke so that the material may be stripped from the punch on the succeeding up-stroke. 60

A device embodying the principles of the present invention is illustrated in the accompanying drawings, in which;

Figure 1 is a view of the device in side elevation. 65

Fig. 2 is a horizontal section on the line 2—2 of Fig. 3, but with parts omitted for better clearness.

Fig. 3 is a transverse vertical section on the line 3—3 of Fig. 2. 70

As shown in said drawings 10 indicates the lower end of the reciprocating head of the punch press and 11 the adjacent portion of the frame structure, those parts of the machine which are not here shown being of 75 approved form, and their particular design not constituting any part of the present invention.

To the under surface of the reciprocating head 10 is secured a heavy plate 15 and below this plate is bolted the part 18 carrying (as hereinafter more particularly described) a tool holder 51 to which is attached the punching implement 20 by means of a nut 52 screwed onto the lower threaded end 53 of 80 the tool holder 51, as shown. The lower part of the nut 52 is milled at 54 to aid in turning it. The part 18, which forms a 85 guide for the tool holder 51, is made with an integral horizontal flange 21 fitting under the plate 15, and with a vertical opening 22 through its length in which the tool holder 51 makes a sliding fit. The tool holder 51 is made with a head or enlargement 23 at its upper end and in the down stroke of the 90 reciprocating head 10 the punch 20 attached to its lower end is forced into the work by the pressure of the plate 15 upon this head or enlargement 23; while it is withdrawn or stripped from the work in the succeeding 95 up stroke by a pair of jaws or gags 26, 26, which grasp the shank of the tool holder 51 below its head 23.

The gags 26 slide horizontally in guide-ways extending laterally from the enlarged 100 upper portion of the vertical bore 22 through the part 18, and below them are two horizontal shafts 28, 28, which are journaled in the part 18. To each of these shafts is fixed a crank arm 30 with a ball 32 at its upper 110

end engaging in an opening in the corresponding gag, so that by the rotation of these shafts the gags are moved inward and outward. At the opposite ends of the shafts 5 28 are fixed bell crank levers 35, each including a substantially horizontal arm and arm extending vertically away from the horizontal arm. The two vertical arms are connected by a spring 40 acting to draw 10 them together and bring the gags into engagement with the tool holder 51; and the gags are separated on up strokes of the reciprocating head 10 by the horizontal arms 37 coming into contact with fixed stops 43, 15 43, extending downward from the punch press frame 11, these stops being threaded and provided with set nuts 44, 44, to permit of vertical adjustment.

In the operation of the press, the gags are 20 automatically withdrawn during the latter part of each upstroke of the reciprocating head 10, and the tool holder 51 with its punch 20 is allowed to drop down upon the work, where it may remain continuously and 25 rest with its own weight only upon and in contact with the work to aid in properly locating the latter. The reciprocating head 10 is then caused to descend for an operative stroke to force the punch 20 through 30 the work. During this down stroke, the spring 40 pulls the arms 35 toward each other, pressing the gags 26 inwardly and, by the time the levers 37 have disengaged the stops 43, the gags will have been moved into 35 substantial engagement with the shank of the tool holder—beneath the head 23. Further downward movement of the reciprocating head will force the punch through the work. On the succeeding up- 40 stroke of the head, the tool holder will be drawn upwardly by engagement of the gags with the shoulder formed below the head 23, and the punch 20 will be stripped from the metal. During this operation, the metal 45 is prevented from rising by a stripper 50 which is fixed to the punch press frame 11 and under which the metal is placed upon the die 61 of the press.

I claim as my invention:

50 1. In a machine of the character described, the combination of a work supporting member, a movable member or head reciprocable toward and from the work supporting member and having a tool-engaging abutment, 55 a tool reciprocably mounted in the movable member, means other than the abutment for automatically connecting the tool to the head during the movement of the head toward the work, and means for automatically breaking such connection when the head has moved a predetermined distance from the work.

2. In a machine of the character described, the combination of a work supporting member, a movable member or head

reciprocable toward and from the work supporting member, a tool reciprocably mounted in the movable member, an abutment carried by the movable member and adapted to be brought into and out of operative relation to the tool, means other than the abutment for automatically connecting the tool to the head for the purpose of moving the tool away from the work, and means for automatically breaking such connection when the head has moved the tool a predetermined distance from the work. 70 75

3. In a machine of the character described, the combination of a work supporting member, a head reciprocable toward and from said member, a tool reciprocably mounted in said head, the head having an abutment which is adapted to engage the tool when the head is moved toward the work, a plunger reciprocably mounted in 80 said head and adapted to engage the tool thereby to connect the same to the head during the movement of the head away from the work, and adjustable means other than said abutment for automatically breaking 85 the connection between the plunger and the tool when the head has moved a predetermined distance from the work. 90

4. The combination, with a reciprocable head and a tool, said head having an abutment adapted to engage the tool on the power stroke of the head, of means other than the said abutment for automatically disconnecting the tool from the head on the return stroke of the head. 95

5. In a machine of the character described, the combination, with a reciprocable head, of a tool carried thereby and longitudinally movable thereof, gags adapted and arranged to engage said tool, and means for automatically moving said gags toward and from the tool, said means including shafts carried by the head and each having an arm engaging a gag, bell-crank levers on each shaft, a spring connecting corresponding bell-crank arms of said shafts, and stops located in the paths of movement of and adapted to engage the other bell-crank arms of said shafts and thereby to rock said shafts in opposition to said spring. 100 110

6. In a machine of the character set forth, the combination, with a reciprocable head, of a tool carried thereby and longitudinally movable thereof, a tool-engaging member carried by said head, and means for automatically moving said member toward and from said tool, said means including a shaft carried by the head, a projection on said shaft adapted to engage said member, a second projection carried by said shaft, a stop adapted and arranged to engage such second projection to move the said member away from said tool, and means tending to move said member toward said tool. 120 125

7. In a machine of the character set forth,

- the combination, with a reciprocable head, of a tool carried thereby and longitudinally movable thereof, a tool-engaging member carried by said head, and means for automatically moving said member toward and from said tool, said means including a shaft carried by said head, an arm carried by said shaft adapted to engage said member, a pair of arms projecting from said shaft, a spring 5 connected to one of said arms and to said head, and a stop in the path of movement of the last-mentioned arm and adapted to rock said shaft in opposition to said spring.
8. In a machine of the character described, 10 the combination, with a work-supporting member, of a reciprocable head having a bore, a tool reciprocably mounted in said bore and having a shouldered portion, said head having a guideway intersecting the 15 said bore, a gag in said guideway adapted to engage beneath the shouldered portion of the tool, means tending to hold said gag in shoulder-engaging position, and means for automatically moving the gag outwardly in 20 its guideway when the head shall have moved a predetermined distance away from the work-supporting member.
9. In a machine of the character described, 25 the combination, with a work-supporting member, of a reciprocable head having a bore, a shouldered tool reciprocably mounted in said bore, said head having a pair of guideways intersecting the said bore, a gag in each guideway adapted to engage beneath 30 the shouldered portion of the tool, means tending to hold said gags in shoulder-engaging position, and adjustable means for automatically moving each gag outwardly in 35 its guideway when the head shall have moved predetermined distances away from the work-supporting member.
10. In a machine of the character described, 40 the combination, with a work-supporting member, of a reciprocable head, a tool reciprocably supported by said head, means acting automatically in a movement of the head toward the work-supporting member to engage the tool therewith to permit it to be withdrawn from said member in 45 a movement of the head away from the work-supporting member, and means acting automatically in the movement of such head away from the work-supporting member for releasing the tool and permitting it 50 to move toward said member.
11. In a machine of the character described, 55 the combination, with a work support, of a reciprocable head, a tool reciprocably supported by said head, a pair of tool-engaging members carried by said head and movable toward and from said tool, means acting automatically in a movement of the head toward the work support to engage the 60
- said members with the tool to permit the latter to be withdrawn from said support in a movement of the head away from the support, and means acting automatically in the movement of such head away from the work support for moving said members away from the tool and permitting them to move 65 toward said support.
12. In a machine of the character described, 70 the combination, with a work-supporting member and provided with a bore having an enlarged upper end, a tool having a head mounted in the enlarged upper portion of said bore and a shank in the reduced portion of said bore, a gag movable in a guideway in said head intersecting the enlarged portion of said bore, means normally holding said gag in operative relation to and beneath the head of said tool, and means for automatically moving the gag away from 75 the tool in and through the movement of the head away from the work supporting member.
13. In a machine of the character described, 80 the combination, with a work-supporting member, of a reciprocable head having a bore provided with an extended enlarged portion and with a reduced portion therebeneath, a tool having a head adapted to reciprocate in the enlarged portion of 85 the bore and a shank adapted to reciprocate within the reduced portion of the bore, said head having guideways intersecting the enlarged portion of the bore, a gag in each 90 guideway, means normally holding said gags in their inward position, and means operated by the movement of the head away from the work-supporting member for automatically moving the said gags outwardly in their respective guideways.
14. In a machine of the character described, 95 the combination, with a work-supporting member, of a reciprocable head having a bore, a tool mounted in said bore and having a shouldered portion, said head having a guideway intersecting the said bore, a gag in said guideway adapted to engage beneath the shouldered portion of the tool, means tending to hold said gag in shoulder-engaging position, and means operative by 100 the movement of the head away from the work-supporting member for automatically moving the gag outwardly in the guideway to disengage said shoulder.
- In witness whereof, I have hereunto subscribed my name in the presence of two witnesses this 18th day of November, 1914.
